DESIGN FOR A JEWELRY FINDING OR SIMILAR ARTICLE

Rayford Kellett and Frank C. Robinson, Leavenworth, Kans.

Application November 9, 1942, Serial No. 108,718

Term of patent 3½ years

To all whom it may concern:

Be it known that we, Rayford Kellett and Frank C. Robinson, citizens of the United States, residing at Leavenworth, in the county of Leavenworth and State of Kansas, have invented a new, original, and ornamental Design for a Jewelry Finding or Similar Article, of which the following is a specification, reference being had to the accompanying drawing, forming part thereof.

Fig. 1 is a front elevational view of a jewelry finding showing our new design.

Fig. 2 is a side view thereof; and

Fig. 3 is a sectional view taken on line 3—3 of Fig. 1.

We claim:

The ornamental design for a jewelry finding or similar article, as shown.

RAYFORD KELLETT.
FRANK C. ROBINSON.
